PHOTOGRAPHIC WASHING APPARATUS

Loyd A. Wildman, Charleston, W. Va.

Application June 1, 1943, Serial No. 489,281

5 Claims. (Cl. 95—97)

This invention relates to photographic washing apparatus, and more particularly to apparatus of this character designed for home or amateur use.

The present application is in the nature of a continuation in part of my prior co-pending application, Serial No. 446,370, filed June 9, 1942.

An object of the invention is to provide apparatus, in the form of a convenient unit, which may be placed upon and supported by any suitable receptacle, such as an ordinary sink or basin, and which is provided with means whereby one or more film holders may be suspended therefrom so as to be immersed in water contained in the receptacle, and whereby such film holders may be continuously reciprocated, so as to thoroughly wash the film.

A further object is to provide improved means for imparting an irregular oscillating movement to the film holders as they are reciprocated, thus producing a more efficient washing operation.

In order that the invention may be readily understood, reference is had to the accompanying drawing forming part of this specification and in which—

Fig. 1 is a side elevation of my improved apparatus as it appears when supported on an ordinary sink or the like, parts being shown in section;

Fig. 2 is a plan view of the apparatus;

Fig. 3 is a fragmentary side elevation thereof looking from the side opposite to that of Fig. 1; and

Fig. 4 is a detailed view showing one of the parts detached.

Referring to the drawing in detail, my improved apparatus comprises a base 1, preferably of elongated form, and which may conveniently consist of a wooden board or the like, to which cleats 1^a are secured. As shown in Fig. 1, this is adapted to rest upon and be supported by any suitable receptacle such as a tub, sink or the like, shown at X.

Secured to the base 1 are a pair of upstanding brackets 2, in which is journaled a transversely extending rock shaft 3.

Fixed to one end of the shaft 3 is a crank arm 4 (see Fig. 3) and this is connected by means of a pitman or link 5, with a crank 6, secured to the end of a shaft projecting from a gear box 7. The gearing in this box is operatively connected to a small electric motor 8, so as to be driven thereby.

From the foregoing, it will be understood that as the motor 8 runs, the gearing in the box 7

will be driven and the crank 6 caused to turn, thus, by means of the link 5 and crank arm 4, oscillating the rock shaft 3. I have shown a flat, open tray 9, secured to the rock shaft at a point between the brackets, said tray being adapted to receive and support a standard developing tank, as set forth in my said prior co-pending application, S. N. 446,370, but such tank forms no part of the present invention and hence is not illustrated herein.

Referring now more particularly to Fig. 2, it will be seen that one end of the shaft 3, designated 3^a, projects laterally beyond the edge of the base 1, and to such projecting end is rigidly secured a horizontally extending bar 10, from each end of which depends a flexible link 11, which, by means of a double ended hook 12, engages and supports a hollow film spool 13. It will be understood that the film spools are thus suspended from the bar 10 in such position that they are immersed in water in the sink or receptacle X. Thus as the shaft 3 is oscillated, the spools 13 are reciprocated in the water in order to thoroughly wash rolls of film which may have just been developed.

The links 11 are preferably constructed as elastic or resilient elements, such as coil springs or rubber bands, so that they are not only flexible, and capable of being twisted, but are also capable of yielding, as the bar oscillates. Thus, whatever the nature of the link 11, this link, together with the hook member 12 carried thereby, constitutes flexible means suspending the film spool in such a manner that it is freely movable in all directions.

In order to impart to the film spools an oscillating movement in addition to their reciprocation, and thus produce an irregular agitating movement for more effective washing of the film, I secure to the lower end of each spool a radially extending paddle or propeller blade 14. This is shown as attached to a hub 15, carried by a rod 16; embedded in a plug 17 of rubber or the like, similar to a bottle stopper. This plug is inserted tightly into the open lower end of the spool. As the spool is moved up and down in the water, by means of the bar 10, the paddle or blade 14 tends to rotate the spool, first in one direction and then in the other, thus producing a kind of irregular oscillation. The irregularity of the movement is further increased by reason of the yielding of the elastic elements 11 which support the spools.

While I have shown a bar 10, providing a pair of arms, each capable of supporting a spool at its

end, it will, of course, be understood that a single arm, attached at one end to the shaft, may be employed instead of the bar, if desired.

From the foregoing, it will be apparent that my improved apparatus is extremely simple in construction and operation, and is designed for handling standard film spools. It will also be clear that the base, on which the driving mechanism is mounted, constitutes a convenient unit which may be readily placed upon and supported by any ordinary household receptacle capable of containing water, such, for example, as a tub, basin, or kitchen sink, and that the cleats 1^a on the under surface of the base are provided to prevent accidental dislodgment of the base from a supporting receptacle.

What I claim is:

1. Apparatus of the class described comprising a portable flat base member adapted to be supported in a horizontal position above any suitable open receptacle containing a liquid, an arm pivotally mounted on said base to swing in a vertical plane, and means by which a film spool may be suspended from said arm at a point clear of and below said base member, in such position as to be immersed in the liquid in said receptacle, said means being flexible, whereby said spool is freely movable in such liquid in all directions, and means on said base member for continuously reciprocating said film spool vertically in the liquid.

2. Apparatus of the class described comprising a base constructed to rest on and be supported in a horizontal position by any suitable receptacle containing a liquid, said base being narrower and longer than said receptacle, an arm pivotally mounted on said base to swing in a vertical plane at a point beyond the side edge thereof, means on said arm for suspending a film spool below said base in such position as to be immersed in the liquid in said receptacle, said means including a flexible link, capable of being twisted, and a member depending from said link and constructed to engage said spool, whereby said spool is freely movable in all directions, and means on said base for continuously oscillating said arm and thus reciprocating said film holder in the liquid.

3. Apparatus as set forth in claim 1, in which additional means are provided for causing the film holder to oscillate as it is reciprocated.

4. Apparatus of the class described comprising a base, an arm pivotally mounted thereon to swing in a vertical plane, a link suspended from said arm, and a hook member carried by said flexible link and constructed to engage a hollow film spool.

5. An attachment for film holders comprising a propeller blade and a plug of resilient material constituting the hub of such blade, said plug being of such size as to fit frictionally within the open end of a film spool.

LOYD A. WILDMAN.
